UNITED STATES PATENT OFFICE.

JOSEPH J. CARR, OF WILKES-BARRÉ, PENNSYLVANIA.

PROCESS OF FORMING CORES.

SPECIFICATION forming part of Letters Patent No. 393,208, dated November 20, 1888.

Application filed May 7, 1888. Serial No. 273,090. (No model.)

To all whom it may concern:

Be it known that I, JOSEPH J. CARR, a citizen of the United States, and a resident of Wilkes-Barré, Luzerne county, Pennsylvania, 5 have invented an Improved Process of Forming Cores, of which the following is a specification.

The object of my invention is to rapidly and accurately form cores for molding pipe and similar structures by compressing the sand in a core box by means of an expanding core-barrel, as fully described hereinafter.

Heretofore cores have generally been made by placing on a central core shell or stick the necessary material for making the core—sand, for instance—and packing this from the exterior by hand, and then when a certain amount of sand is applied to the body of the core the superfluous sand is scraped off by means of a stationary scraper and the core itself revolved against the scraper until the correct diameter is obtained. This process is very laborious and occupies considerable time, and is not at all times correct. I overcome this difficulty 25 and proceed in the following manner with the following devices, reference being had to the accompanying drawings, in which—

Figure 1 is a longitudinal section of my improved core-box and central core-barrel contracted, with the sand between the central core-barrel and the mold or box. Fig. 2 is a longitudinal section with the core-barrel extended to its fullest diameter, compressing the sand between it and the core-box. Fig. 3 is a transverse section on the line 3 3, Fig. 1. Fig. 4 is a transverse section on the line 4 4, Fig. 2. Fig. 5 is a view of a portion of the pipe-mold and the core in position therein, showing the cast pipe between the mold and 35 the core; and Fig. 6 is a modified form of compressor for the flange-core. Fig. 7 is a view of one of the bearings, showing the hinged cap.

Referring to Fig. 1, A is the base plate or table on which the device is mounted, and *a a* 40 are suitable bearings for the central tubular shaft or core barrel, B. The bearings have hinged or movable caps, so that the whole device can be lifted from the bearings, for a purpose described hereinafter.

Secured to the base-plate A is the drag or lower half of the core-box D, and attached to this box in any suitable manner is the up-

per portion or cope, D', of the box. These two sections, in the present instance, are secured together by means of hinges on one side 55 and slip-bolts passing through lugs on the other side.

The molds in the present instance are made to form what is known as a "large steam-pipe," this pipe having large flanges at each end, 60 through which bolts pass, the flanges being faced to make a tight joint; but it will be understood at the outset that any shape of pipe may be formed, the shape of the pipe depending altogether upon the formation of the core- 65 box and pipe-mold.

The shaft B passes centrally through the core-box and is hollow, and through the center of this hollow shaft is a shaft, E, having screw-threads *e e'* at each outer end, and adapted to these screws are suitable nuts, F F'.

Secured to the operating-shaft E are, in the present instance, two sleeves, *b b*, and pivoted to these sleeves are links *c c*, pivoted in turn to lugs on the core-barrel proper, C C. This 75 core-barrel is made in this instance in four sections, each connected to the operating-shaft by independent links. The adjoining sections of the core-barrel overlap each other, as shown in the transverse section, Fig. 3, so that the 80 joints will be broken. This core-barrel has a number of perforations in its periphery to allow for the escape of the gases produced in casting, and also has a series of lugs on its periphery, by which the molding-sand is retained 85 in position on the barrel. Each of these sections is provided with pins *ff*, radiating toward the center and adapted to slide in orifices in the hollow shaft B, so that each section of the core-barrel is guided by this hol- 90 low shaft.

Referring to Fig. 1, if the nuts F F' are turned in the direction of the arrow, it will cause the operating-shaft E to move in the direction of its arrow, expanding the core to the 95 position shown in Fig. 2; but if the nuts F F' are turned in the direction of the arrow, Fig. 2, it will contract the core, as shown in Fig. 1. On the shaft B is a sleeve, H, having a wide flange, *h*. This flange is of the same diameter as the enlarged end portions, *d d'*, of the core-box D D'. In the rear of the sleeve H is a handled nut, I, adapted to a screw-thread on the shaft B. By turning this nut in one di-

rection it will force the sleeve and its flange toward the core-box. This flange h forms the core for the flange of the pipe, and the sand to form this portion of the core is compressed 5 at the same time the body of the core is compressed.

In the drawings I have shown two sleeves, H H' ; but in some cases only one sleeve may be used when it is desired to make single-flanged 10 pipe.

In place of the nut and screw on the shaft a plate, H' , may be secured to the shaft and toggle-levers i inserted between the plate and the flange h or h' , and a link, i' , may be used for 15 connecting the toggles with a fixed sleeve on the operating-shaft E , so that simultaneously with the movement of the sections of core-barrel the flanges h h' will also move, as shown in Fig. 6.

20 The mode of operation is as follows: The cope portion D' of the core-box is removed, and also the central expanding core. Sufficient sand is placed in the drag to supply one-half of the core, and is then shaped as nearly 25 as possible by means of a sweep. The contracted core is placed in position on its bearings and sand is then packed upon this core-barrel, after which a second sweep is used to clear off the superfluous sand. The cope 30 is then placed in position and locked to the drag. The nuts are turned, expanding the core-barrel from the position shown in Fig. 1 to that shown in Fig. 2, compressing the sand between the core-box and core-barrel. The 35 openings and the projections on the core-barrel prevent the displacement of the sand. Simultaneously with the expanding of the core-barrel the end flanges, h h' , are moved, compressing the sand to form the core for the

flanges of the pipe. The cope is then removed 40 and the core lifted out of the box and placed in position in the pipe-mold W , as shown in Fig. 5, and the metal is poured in between the mold proper and the core, thus forming the pipe, as shown by heavy black lines in Fig. 5, 45 after which the core-barrel is retracted by releasing the operating-shaft and can be readily pulled out from the cast pipe, as in ordinary pipe-molding.

I claim as my invention—

1. The mode herein described of forming cores for casting pipe and similar articles, said mode consisting in providing a core-box of the shape of the pipe to be cast, inserting therein an expandible core-barrel in its contracted form, filling the space between the contracted core-barrel and core-box with sand or similar casting material, and expanding said core-barrel, thus compressing the sand to the proper density, substantially as set forth. 55

2. The mode herein described of forming cores for casting flanged pipe, said mode consisting in providing a core-box of the shape of the pipe to be cast, a collapsible core-barrel with movable flanges, packing sand or other 65 material between the core-barrel flanges and core-box, and expanding the core-barrel and moving the flanges toward the core-box, so as to compress the sand into the compact form required, substantially as set forth. 70

In testimony whereof I have signed my name to this specification in the presence of two subscribing witnesses.

JOSEPH J. CARR.
